UNITED STATES PATENT OFFICE.

FREDERICK D. VAN NORMAN AND GEORGE W. FLEMING, OF SPRINGFIELD, MASSACHUSETTS, ASSIGNORS TO VAN NORMAN MACHINE TOOL COMPANY, OF SPRINGFIELD, MASSACHUSETTS, A CORPORATION OF MASSACHUSETTS.

GRINDING MACHINE.

Application filed May 19, 1922. Serial No. 562,104.

This invention relates to improvements in grinding machines.

According to one feature of this invention, a grinding machine is provided which consists of a plurality of units, each of the vertical type, which are arranged in a compact group and may be mounted on a common base and driven from a common source of power, preferably self contained in the machine, as an electric motor.

For example, by this arrangement three grinding units of the vertical type may be arranged into such small compass as to occupy no more floor space than one grinder of the horizontal type of like capacity. Aside from the desirable feature of economy in floor space, the three units are grouped so closely together that one man may not only operate all three but may continually have all three machines under close observation.

According to another feature of the invention, the machine has a main power shaft which is common to all the units and is suitably driven, preferably by an electric motor, and a series of driving shafts, one for each unit and each arranged to be driven independently of the other from the main power shaft, whereby any one or more of the units may be operated, as desired.

According to another feature of the invention, a grinding machine is provided wherein the work-head and wheel-head are relatively movable in a vertical direction, and the movable head, together with the parts carried therewith, such as a rotary spindle and driving mechanism therefor, is balanced on its ways by distributing the weight of the head and parts carried thereby equally on opposite sides of said ways.

According to a further feature of the invention, the movable head is also counterbalanced on its ways against vertical movement.

According to another feature of the invention, the wheel-head is mounted on one side of a carriage, which is slideable intermediate its ends on vertical ways, and on the opposite side of said carriage, a driving means, preferably an electric motor, is mounted.

According to other features of the invention, provision is made for cross feed movement of the work-head or wheel-head, either or both, and provision is likewise made for quickly moving either the wheel head or work head into offset relation with the other,

and for rapidly bringing them back accurately into their original positions.

Other features and advantages will appear in the following description and in the illustrative embodiment of the invention in the accompanying drawings, in which:

Fig. 1 is a front elevational view of a multiple grinding machine embodying the invention;

Fig. 2 is a fragmentary plan view, with parts broken away, of the rear portion of the machine, illustrative of the common driving means for the several units and the manner in which power from such means is distributed to the several units;

Fig. 3 is an enlarged side elevational view, with parts in section, of the lower portion of one unit of the machine;

Fig. 4 is a fragmentary sectional plan view, illustrative of the driving connections for the work-holder;

Fig. 5 is an enlarged side elevational view of the upper portion of the machine;

Fig. 6 is a sectional plan view illustrative of the wheel-head and associated parts;

Fig. 7 is a sectional plan view illustrative of the driving connections for the wheel spindle;

Fig. 8 is a fragmentary sectional plan view of the means for releasing the wheel-head from its feeding mechanism; and

Fig. 9 is a fragmentary view taken on the line 9-9 of Fig. 3.

Referring to these drawings, the machine includes a series of units (three as shown) mounted on a common base A. All of these units are alike, so that one only need be described in detail, and each unit is a complete grinding machine in itself and may be used independently of the others, if desired. Each of the unit grinding machines is preferably of the vertical type, as indicated in Fig. 1, to afford a very compact arrangement and one in which the three machines occupy no more floor space than a single machine of like capacity and of the horizontal type. Aside from the saving of floor space, which is most important, the compact arrangement shown is desirable to permit one operator to efficiently attend a number of machines. The three machines are grouped together closely enough to allow the necessary close observation of the work being performed by the three machines.

Each of these units includes a hollow base frame B within, and on the back of which, most of the driving mechanism is located. A single driving means, such as an electric motor M supplies power to all the units. As shown in Fig. 3, motor M is mounted on a pedestal C located at the rear of the bed A and is provided with a pulley 15 which by means of a belt 16 drives a pulley 17 on a shaft 18 extending horizontally along the rear wall of the three frames B adjacent the bases thereof. Above shaft 18, a series of axially aligned shafts 19, one for each unit, are mounted and each shaft 19 carries tight and loose pulleys 20 and 21, either of which may be connected by a belt 22 to corresponding pulleys 23 and 24, respectively, on shaft 18. By this arrangement, any one or more of shafts 19 may be driven as desired.

Each shaft 19 has fixed thereto stepped pulleys 25 and 26 located on opposite sides of the pulleys 20 and 21. These pulleys 25 and 26 are connected by belts 27 and 28 to similar pulleys 29 and 30, respectively, located within frame B. The pulley 29 is fixed to a shaft 31, rotatably supported from frame B, and this shaft is the driving shaft for feeding the wheel-head toward and away from the work-head and for effecting cross-feeding movements of the former. The pulley 30 is fixed to a shaft 32 suitably mounted in frame B and this shaft is the driving shaft for rotating the work-holder spindle.

The work-holder, of any desired type, may be suitably secured to the work-holder spindle 34, which, as shown, has a threaded upper end for such purpose. The spindle 34 is rotatably mounted and vertically disposed in a work-head 35 and at its lower end carries a pulley 36 which is connected by a belt 37 to a pulley 38 on the driving shaft 32, already described. This belt 37 necessarily has to make a quarter turn and desirably passes over two idler pulleys 39 and 40, as best shown in Fig. 4. These pulleys are mounted on studs 41 secured in a bracket 42 pivoted at 43 to the work-head 35 and a spring 44, connected at one end to the work-head and at the other end to bracket 42, urges the pulleys 39 and 40 against the belt. The particular mounting of these pulleys as described is desirable to compensate for movement of the work-head in a direction parallel with the axis of shaft 32.

The work-head 35 may be mounted on frame B in many various ways, as desired, and the driving connections for the work-holder spindle 34 have been designed to permit movements of the work-head relatively to the frame, which movements are frequently, although not always, desired. In the drawings, several examples of frequently desired movements are shown, and any one or more may be utilized as desired. Thus,

the work-head 35 is secured to a member 46 in such a manner as to permit angular adjustment thereof in a vertical plane, as by bolts 47 passing through arcuate slots 48 in the work-head. This member 46 may, as shown, constitute a slide mounted on ways 49 on a member 50 and the latter may be similarly mounted to slide on ways 51 formed on the frame B. As shown, the slides 46 and 50 are movable in a horizontal direction for the purpose of moving the work-holder at right angles to the axis of the grinding wheel, which as will appear, is located above the work-holder spindle and with its axis vertically disposed.

One of these slides, as 50, is arranged to be moved automatically by small increments for cross-feeding purposes by a more or less common mechanism exemplified in Fig. 3. A lead screw 52, rotatably mounted in frame B, engages a nut 53 on slide 50 and this lead screw is connected by gearing 54 to a shaft 55 which carries a ratchet 56. The latter is intermittently turned, and when so turned, moves the slide in a manner too well known in the art to require complete detailed illustration and description here. Ratchet 56 is provided with the usual holding pawl 57 and a second pawl 58 pivoted to one end of a lever 59 pivoted intermediate its ends to frame B and arranged with its other end in the path of a reciprocable member 60. The latter periodically engages and depresses the last named end of lever 59 thereby causing the pawl 58 to turn ratchet 56 through an angular increment which, as will appear, is variable as desired. On an upward movement of the reciprocable member 60 the pawl 58 is moved back by gravity, the left hand portion of the lever and the pawl 58 over-balancing the other end of the lever. The member 60 takes the form of a rod, having a screw threaded connection with a bracket 61, and is thereby adjustable to vary the time at which it will engage lever 59 and thus the extent of movement imparted thereto. The bracket 61 is connected by a clamping bolt 62 to a bracket 63 carried by the wheel head and by loosening bolt 62, bracket 61 may be swung on this bolt as a pivot into a position such that it will not engage lever 59 and may be held in this new position by tightening bolt 62.

The other slide 46 is provided in cases where it is desired to move the work holder rapidly into an offset relation with the grinding wheel to permit convenient testing and inspection of the work and to later return it accurately into its former position. That is, it is desired to move the work-head without disturbing the cross feed mechanism just described. The slide 46 is normally clamped to the slide 50 in a suitable manner to permit its quick and convenient release. For example, it may be clamped by a screw

65, threaded into slide 46 and bearing at its inner end against slide 50. Also an abutment is provided on one slide to engage the other slide and define the relative positions 5 in which they should be locked together by screw 65. Thus, a screw 66 threaded into a lug 67 on slide 50 is arranged to engage one end of slide 46. For moving slide 46, a lever 68 is provided, which is pivoted to frame B at one end and pivotally connected, as by a link 69, to the slide. On releasing screw 65, lever 68 may be swung to the left (Fig. 1) to move slide 46, and thus the work holder, into the desired offset position. In 10 returning slide 46 to its normal position, lever 68 is moved until the slide abuts screw 66 after which the screw 65 is tightened, whereby slides 46 and 50 may be clamped together in the same relative positions which 15 they originally occupied.

10 Superposed upon frame B is a second frame D which on its front face is provided with two laterally spaced and vertically extending ways 70, as best shown in Figs. 1 and 6. Upon these ways a carriage 71 is 15 slidably mounted, and upon ways 72 provided on the carriage, a slide 73 is mounted for horizontal movement. A second slide 74 may be mounted on ways 73, provided on 20 slide 73, if desired. The slide 74 rotatably supports a vertically disposed wheel spindle 76 which carries at its lower end a grinding wheel 77 and at its upper end a pulley 78.

25 Secured to carriage 71 and extending rearwardly thereof inside frame D is a frame 79 upon which is mounted an electric motor 80, preferably in a manner to permit adjustment as by the bolts 81 passing through slots 82 in the base of the frame. A screw 83, 30 rotatably mounted but not axially movable in a lug 84 on frame 79, is threaded into the base of motor 80 to permit the latter to be conveniently adjusted back and forth on frame 79 when bolts 81 are loosened. The 35 shaft of motor 80 carries a pulley 85 which is connected by a belt 86 to the pulley 78 described. A belt tensioning device is provided such as an idler pulley 87 mounted on one end of a lever 88, which is pivoted 40 intermediate its ends at 89 to the top of carriage 71 and connected at its other end by a spring 90 to the carriage. The spring urges the idler against belt 87 to tension it at all 45 times and compensate for movement of slide 74, this arrangement being particularly desirable where a quick acting offset movement of the slide is desired.

50 A quick acting means for moving slide 74 to carry wheel 77 into offset relation to the work spindle may be provided, which is generally similar to that described for the work head. Thus, slide 74 normally abuts a stop, such as a screw 91 (Fig. 6) carried by slide 55 73, and is clamped thereto as by a screw 92 (Fig. 5). A lever 93 (Fig. 1), pivoted to carriage 71, is connected to slide 74, as by a pin and slot connection 94, whereby when screw 92 is loosened, lever 93 may be swung to move slide 74 rapidly to the left (Fig. 1). In returning slide 74, lever 93 is swung until 60 the slide abuts screw 91, after which screw 92 is tightened to clamp slides 74 and 73 together in the same relative positions which they originally occupied.

65 Automatic cross-feeding means may be provided for moving the slide 73 and thus the wheel 77, one example of such means being shown in Figs. 5 and 6. Thus, slide 73 carries a nut 94, and engaged therewith, is a lead screw 95 rotatably mounted, but 70 not axially movable in the carriage 71. The latter, as indicated in Fig. 6, is suitably recessed to receive these elements. The lead screw 95 is connected at one end by spur gears 96 to a stub shaft 97 which is rotatably mounted in a bracket 98 secured to carriage 71, and upon this shaft is fixed a ratchet wheel 99 and a hand wheel 100 (Fig. 6) the latter being employed for manually moving the slide when desired. An actuating pawl 101, pivotally connected to the free end of an arm 102 pivoted to bracket 98, is arranged to be lifted by a pin 103 mounted to slide vertically in the bracket and limited in its descending movement by a collar 104 on its upper end. Pin 103 is preferably adjustable, as to length, by means of an extension 105 threaded therein. The lower end of the member 105 is adapted, on descent of carriage 71, to engage an abutment 106, which is mounted on a vertical rod 107 and adjustably secured thereto, as by the clamping screw 108. The rod 107 is mounted in brackets 109 secured to frame D. The time 10 at which the abutment 106 is engaged by member 105 may be varied by adjustment of the former on rod 107, and by varying this time of engagement, the movement of pin 103 and thus the throw of pawl 101 may be varied. The abutment 106 may be moved 15 angularly out of the path of member 105 when this cross-feeding movement is not desired.

10 Secured to carriage 71 and the attached motor supporting frame 79 are arranged on opposite sides of ways 70 and preferably the weight of these elements and the parts carried thereby is distributed, as nearly as possible, equally on opposite sides of these ways. The result of this arrangement is a balancing of the carriage and its attached parts, which if perfectly performed will relieve the ways 70 from pressure and therefore minimize wear. The carriage 71 can be made to engage its ways with very little allowance for clearance and yet avoid the binding action which would otherwise occur, and a closer fit between the ways and carriage 15 means improved accuracy in the work performed.

The carriage 71 is preferably also balanced against movement on its ways 70, or more properly its weight, including attached parts, is counterbalanced by a weight 115 (Fig. 5) so that the carriage will tend to remain in any of the positions to which it may be moved. This arrangement reduces the effort required to raise the carriage and relieves the mechanism, used for vertically moving it, from a considerable weight or pressure which would tend to cause rapid wear. The counterbalance 115 is preferably guided on a rod 116 fixed to, within, and near the rear of frame D and is connected 15 by a chain 117 to carriage 71, the chain passing over one or more sheaves 118 mounted on frame D.

The carriage 71 is moved on its ways 70 by a vertically reciprocable rod 119, which is slidably mounted in frame B (Fig. 3) and extends upwardly into frame D, passing loosely through the motor supporting frame 79, as indicated in Fig. 6. Adjustably fixed on rod 119 is a collar 120 (Fig. 8) which has 20 a groove 121 in its periphery disposed at right angles to the axis of rod 119. Slidably mounted in carriage 71 is a pin 122, one end of which is adapted to engage in groove 121 to lock the carriage thereto. A spring 123 25 is provided, which tends at all times to urge pin 122 toward rod 119, and a lever 124 pivoted intermediate its ends to the carriage has a pin and slot connection 125 with pin 122, whereby the latter may be withdrawn 30 from groove 121 to release the carriage 71 for manual movement. For effecting such movement, a hand wheel 126 (Fig. 1) is provided on the end of a shaft 127 which is rotatably mounted in frame D and extends 35 40 into the interior thereof, as shown in Fig. 5. On shaft 127 and within frame D is a pinion 128 which meshes with a rack 129 secured to the carriage 71 as shown in Fig. 6.

The means for automatically reciprocating 45 rod 119 may take various forms, as desired, and one suitable form is given by way of illustrative example in Figs. 3 and 9. Pivotally connected at one end to a collar 130 on rod 119 near the lower end thereof is a link 50 131 which extends downwardly and is pivotally connected to a slide 132. The latter is dovetailed to fit over ways 133 formed on one face of a lever 134 pivoted at 135 to frame B, within which all the actuating mechanism for rod 119 is located. A lead screw 136 is rotatably mounted, but not axially movable, in one end of lever 134 and engages in a nut 137 carried by slide 132. By means of a hand wheel 138 on screw 136, 55 60 the latter may be conveniently turned to adjust the slide 132 along lever 134 and vary its distance from the pivot 135 and thereby vary the throw imparted to link 131 and rod 119. The lever 134 carries on its opposite 65 face a roll 139 which rides in a path cam

140, of suitable configuration, so that the lever is swung up and down on its pivot through an arc of fixed degree. Cam 140 is fixed to one end of a shaft 141 mounted within frame B and on the other end of this shaft 70 is a worm gear 142 which is driven by a worm 143 on the described driving shaft 31.

The machine may be operated in various ways as desired. For example, either the work-head or the wheel-head may be fed 75 transversely, as desired, and these cross-feeding movements may be effected manually or automatically as desired. The automatic cross-feed for both the work-head and wheel-head may be temporarily disconnected, when 80 desired. When one is used, the other is disconnected and when hand-feeding is desired, both may be disconnected. Also both wheel-head and work-head are provided with 85 means for quickly moving the wheel and work-head into off-set relation. Either of these quick acting means may be used, as desired. The relative vertical movement between the wheel and work-head may be effected either manually or automatically, 90 and as shown, is effected by moving the wheel-head. The workhead also may be adjusted so that its axis lies in angular relation with that of the wheel head. It will thus be seen that the machine has considerable 95 flexibility and may be operated in various ways as desired. The general operation of the machine will be obvious from the foregoing description.

The invention has been disclosed herein for 100 illustrative purposes but the scope of the invention is defined by the appended claims rather than by the foregoing description.

What we claim is:

1. In a grinding machine, a frame, a work-head and a wheel-head mounted thereon one vertically above the other, one of said heads being vertically movable to and from the other, a rotary spindle in each head, means for moving one of said heads transversely relatively to its spindle's axis for cross-feeding purposes, and quick acting means for moving the last named head transversely to offset its spindle from the spindle in the other head.

2. In a grinding machine, a frame including a base portion and an upwardly extending portion provided with ways, a work-head mounted on the base portion, a rotary work-holder mounted in said head, a second head slidably mounted on said ways, a rotary tool-carrying spindle mounted in the second head, a motor for driving said tool-carrying spindle, means for moving the second head on its ways, and a second motor for 110 115 driving the last named means.

3. In a grinding machine, a frame having an upwardly extending portion provided with ways, work-holding and tool-carrying devices, the former mounted on said frame 120 125 130 135 140

and the latter slidably mounted on said ways, a rotary spindle mounted in each of said devices, means for adjusting the work-holding device on said frame to permit the 5 work holding spindle to be moved angularly of the tool carrying spindle, means for moving the slideable device on its ways, and means for moving one of said devices transversely to the direction of travel of the slideable device on said ways.

4. In a grinding machine, a frame having an upwardly extending portion provided with ways, work-holding and tool-carrying devices, the former mounted on said frame 15 and the latter slidably mounted on said ways, a rotary spindle mounted in each of said devices, means for adjusting the work holding device on said frame to permit the work holding spindle to be moved angularly 20 of the tool carrying spindle, means for moving the slideable device on its ways, means for moving one of said devices transversely to the direction of travel of the slideable device on said ways, and counterbalancing 25 means for supporting the slideable device in any of the various positions to which it may be moved on said ways.

5. In a grinding machine, a hollow, box-like pedestal provided with an opening in 30 one vertical face thereof and ways on said face on each side of said opening together with ways on the vertical walls of said opening, a carriage mounted for vertical reciprocating movement on said ways, a rotary 35 spindle mounted in said carriage, a motor support secured to that portion of the carriage disposed between the ways and ex-

tending into said hollow pedestal, a motor mounted on said support, and driving connections between the motor and spindle.

6. In a grinding machine, a hollow, box-like pedestal provided with an opening in one vertical face thereof and ways on said face on each side of said opening together with ways on the vertical walls of said opening, a carriage mounted for vertical reciprocating movement on said ways, a rotary spindle mounted in said carriage, a motor support secured to that portion of the carriage disposed between the ways and extending into said hollow pedestal, a motor mounted on said support, driving connections between the motor and spindle, a weight to counterbalance the carriage slideable in the hollow pedestal out of the path 55 of the motor support, and a flexible connection between said weight and carriage.

7. In a grinding machine, a base having an upwardly extending portion with slide ways thereon, a slide supported for vertical 60 movement on said ways, a wheel head mounted on said slide for movement in a direction right angularly to the direction of the first named ways, a work head supported on a vertical face of said base for adjustable 65 movement on an axis angularly to said face, a rotary spindle in each of said heads, means for driving said spindles and reciprocating means for the wheel head.

In testimony whereof we have affixed our 70 signatures.

FREDERICK D. VAN NORMAN.
GEORGE W. FLEMING.
